ATTORNEYS

UNITED STATES PATENT OFFICE.

PASCAL M. KELLY, OF DALHART, TEXAS.

SPUR.

1,397,966.

Specification of Letters Patent.

Patented Nov. 22, 1921.

Application filed March 23, 1921. Serial No. 454,688.

To all whom it may concern:

Be it known that I, PASCAL M. KELLY, a citizen of the United States, and a resident of Dalhart, in the county of Dallam and State of Texas, have made new and useful Improvements in Spurs, of which the following is a specification.

This invention relates to spurs and more particularly to the attaching means for the same.

An important object of this invention is to provide novel means whereby the attaching buttons on a spur may be swingingly connected to the band of the spur in such manner that the same will lie flatly in contact with the ankle portion of the boot so as not to scrape or wear the boot.

A further object of the invention is to provide novel means whereby the swinging button attached to the arm of a spur may be readily renewed without the exercise of unusual skill.

A further object of the invention is to provide an efficient and neat swinging button to be used on any style of spur.

Other objects and advantages of the invention will be apparent during the course of the following description.

In the accompanying drawing:

Figure 1 is a perspective of a spur having the improved attaching buttons,

Fig. 2 is an end elevation of the spur,

Fig. 3 is an elevation of a bracket embodied in the invention, and

Fig. 4 is a detail view illustrating the attaching button of the spur in its operative position.

In the drawing the numeral 5 generally designates a spur which includes a U-shaped band having spaced arms 6 and a bite or connecting portion 7. As illustrated in Fig. 1, the spur is provided with a longitudinally curved shank 8, to which a goad or rowel 9 is connected. The terminal portion of each arm 6 is provided with a U-shaped bracket generally designated by the numeral 10, and which is provided with apertured ears 11 adapted for the reception of rivets or other fastening elements 12. Each U-shaped bracket 10 lies flatly in contact with the outer side of the adjacent arm or band 6, and is provided with a bite or connecting portion 13 which as illustrated in Fig. 2, extends above the upper edge of the U-shaped band.

Each bracket 10 constitutes attaching means for an arm generally designated by the numeral 14 and which is formed from a single length of metal bent upon itself into intermediate ends to form inner and outer limbs 16 and 17 respectively. At the juncture of the limbs 16 and 17 the length of metal is formed with a transversely extending lateral projecting barrel or sleeve 18 which rotatably receives the bite portion 13 of the bracket 10 whereby the arm 14 is swingingly connected to the bracket 10. As illustrated in Fig. 4 the inner limb 16 of the arm 14, is flush with the inner side of the band so that when the spur is applied the arm 14 will lie flatly in contact with the heel or ankle portion of the boot. It will be observed that the arm 14 is arranged entirely above the band and therefore lies flatly in contact with the boot so that the end of the arm will not scratch or lacerate the boot.

The end portions of the limbs or branches 16 and 17 are connected by the shank 19 of a button 20, to which a retaining strap 80 is adapted to be connected.

In the manufacture of the improved swinging buttons the arms and the brackets are constructed separately and are united prior to the attachment of the bracket to the spur. The improved swingers and brackets may be readily attached to the spur band by means of the rivets 12 and should the swinger become worn as the result of continued use, the same may be readily renewed by simply removing the rivets 12 and attaching a new bracket and arm.

As illustrated in Fig. 4 no parts of the arm or swinger protrude through the band and contact with the boot so that the inner side of the band is left entirely smooth.

These improved swinging buttons may be sold without the spur and the purchaser can easily attach them to old spurs by drilling holes in the band or arms of the spur and riveting them on.

I claim:

1. A spur comprising a band, a U-shaped bracket having arms secured flatly in contact with the outer side of the band and having a bite portion arranged above the upper edge of the band, an arm inclusive of a pair of limbs and a bearing member receiving the bite portion of said bracket, and a button having a shank connecting the

terminal portions of said limbs, one of said limbs being adapted to lie flush with the inner side of said band.

2. An attachment for spurs comprising a
5 U-shaped bracket having means whereby
the same may be secured to the band of a
spur and having a bite portion, and an arm

inclusive of a pair of limbs and a bearing member receiving the bite portion of said bracket, and a strap engaging member having a shank extending through and connecting the terminal portions of said limbs. 10

PASCAL M. KELLY.
